Patented Dec. 16, 1919.

UNITED STATES PATENT OFFICE.

ROBERT E. CARMICHAEL, OF DAMON, TEXAS, ASSIGNOR OF ONE-HALF TO GEORGE HAMMAN, OF HOUSTON, TEXAS.

PUMP.

1,325,077.

Specification of Letters Patent.

Patented Dec. 16, 1919.

Application filed February 1, 1919. Serial No. 274,491.

To all whom it may concern:

Be it known that I, ROBERT E. CARMICHAEL, a citizen of the United States, residing at Damon, Brazoria county, Texas, 5 have invented a certain new and useful Improvement in Pumps, of which the following is a full, clear, and exact description, such as will enable others skilled in the art to which it appertains to make and use the 10 same.

My invention relates to improvement in pumps for use in deep wells and has special reference to means for preventing the entrance of sand between the working barrel 15 and the plunger.

In deep well pumping, especially in the use of pumps in oil wells, a large amount of sand is often encountered and difficulty is experienced in preventing wear about the 20 working parts of a pump, due to the entrance of sand about the same.

The object of my invention is to provide 25 resilient metallic rings in the outer surface of the plunger which will act to close the space between the plunger and the working barrel in such manner that little, if any, sand will find entrance thereto and thus increase materially the period during which the plunger will maintain a tight fit in the 30 working barrel without a repairing of the parts.

Referring to the drawings, wherein like numerals are applied to like parts in both the views, Figure 1 is a central longitudinal 35 section illustrating a pump plunger provided with my improvement. Fig. 2 is a transverse section of the pump shown in Fig. 1, taken on the plane indicated by the line 2-2 in Fig. 1.

40 The figures show the pump installed in an outer well casing 1. The working barrel 2 is spaced centrally within the casing and is provided at its lower end with a coupling 10, by which it may be secured to an anchoring 45 means not shown. Within the working barrel is the hollow sucker rod 3, which is shown in threaded engagement with the upper end of the plunger 4. The plunger 4 is provided at its lower end with an ordinary valve cage 5, having a lower seat 6 for the ball valve 7. The said ball valve is prevented from movement upwardly out of the cage by means of a cross bar 8 arranged diametrically across the valve chamber. At 55 the lower end of the working barrel is lo-

cated the usual foot valve chamber 9 provided with an upwardly opening ball valve 11.

As will be apparent from the drawing, when this pump is used in handling fluid 60 mixed with sand, the sand will work up around the lower end of the plunger and find entrance between the plunger and the working barrel. By so doing the sand will cause excessive wear between the plunger 65 and the working barrel, with the result that the tight fit necessary between the two parts, to cause the proper suction, will be destroyed and the plunger will have to be removed and repaired. This is especially the 70 case where ordinary cups of canvas or leather are used to maintain a tight fit between the plunger and the working barrel. I have, however, invented a resilient ring 12 which is adapted to fit within annular recesses 13 in the two ends of the plunger and by their resiliency maintain so close a contact with the side of the working barrel that practically no sand will find entrance thereto. I have found that two of these 80 rings at each end of the plunger will serve the purpose satisfactorily. These resilient rings are preferably made of hardened steel, but it is obvious that they may be made of any similar substance whether metal or 85 otherwise, which will act to spring outwardly against the sides of the working barrel and maintain the close fit necessary in the pumping operation.

As shown especially in Fig. 2, the resilient 90 rings 12 are made slightly thinner on one side than on the other and the ring is split on the thinner side, as shown at 14. This structure of ring is arranged so that the broader side of the ring will completely 95 fill the space between the inner face of the slot in which it is mounted and the inner surface of the working barrel. On the opposite side where the ring is somewhat thinner the resiliency of the ring will force the 100 same outwardly so as to close the space between the plunger and the working barrel in an obvious manner. When in this position the ends of the ring should contact with each other so that no appreciable amount of 105 grit or sand could pass through the opening between the ends. The position of the two rings at each end of the plunger is such that the thick side of one ring will come opposite the thinner side of the ring ad- 110

jacent. This will serve to stagger the opening which might be appreciable as the wear on the ring becomes noticeable and sand finding entrance past the opening on one 5 ring would not easily work past the opening between the ends of the split ring next adjacent thereto.

It will be apparent that this construction is very similar to constructions used in 10 pistons of engines, but so far as I am aware it has never been used in reciprocating pumps where the use of the ring serves to prevent wear by sand. I do not claim broadly to be the originator of rings such 15 as here disclosed for use broadly in pistons, but I believe that I am the first to

use this or any similar structure for the purpose disclosed herein.

What I claim as new and desire to protect by Letters Patent is:

Means for preventing the entrance of sand between the plunger and working barrel of pumps, comprising resilient metallic rings seated in grooves at both ends of said plunger, said rings being split and thinner 25 on one side than on the other and adapted thereby to be pressed into resilient contact with the inner surface of the working barrel and maintain a close fit on all sides.

In testimony whereof, I hereunto affix my 30 signature this the 27 day of January, 1919.

ROBERT E. CARMICHAEL.
